UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

TWIST-DELIVERY GUIDE FOR ROLLING-MILLS.

No. 899,518.

Specification of Letters Patent.

Patented Sept. 29, 1908.

Application filed December 15, 1902. Serial No. 135,244.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Twist-Delivery Guides for Rolling-Mills, of which the following is a specification accompanied by drawings, forming a part of the 10 same, in which—

Figure 1 is a front elevation of a roll housing and a pair of rolls with one of my improved twist delivery guides. Fig. 2 is a vertical sectional view on line 2—2 Fig. 1. 15 Fig. 3 is an enlarged plan view of the delivery guide detached from the roll housing. Fig. 4 is a side elevation of the pair of guide plates removed from their supporting frame. Fig. 5 is a top view of the lower guide plate. Fig. 20 6 is an end view of the entrance end of the guide with a bar between the guide plates, showing the position of the bar as it enters the guide, and Fig. 7 is an end view of the delivery end of the guide with a bar between 25 the guide plates, showing its position as it leaves the guide.

Similar reference letters and figures refer to similar parts in the different views.

The object of my present invention is to 30 provide means for regulating with precision the initial twist to be given a metal bar as it is delivered from one set of rolls, in order to impart a predetermined degree of twist to the bar by the time it arrives at the next succeeding set of rolls; and this is brought about by passing the bar through a guide comprising a pair of guide plates capable of adjustment to give the required initial angular torsion to deliver the bar to the next set of rolls 40 in the exact position to enter their grooves.

Referring to the accompanying drawings, A denotes a roll housing, and B, C, a pair of rolls having grooves D and E and provided with one of my twist delivery guides in which 45 1 denotes a base plate secured upon a bracket 2 by a bolt 3 and capable of vertical adjustment to bring the guide to the required elevation relative to the rolls B and C.

Erected at opposite edges of the base plate 50 and preferably integral therewith are the sides 4 and 5. A pair of guide plates 6 and 7 are held between the vertical sides 4 and 5 and supported upon the base plate 1 so as to bring the space between their opposing surfaces 55 in position to receive a bar as it issues

from between said rolls. The lower guide plate 6 rests upon the base plate 1, and is provided upon opposite edges with projecting cheeks 8, 8 and 9, 9, which contact with the sides 4 and 5 and hold the guide plate from lateral movement. Arms 10, 10 and 11, 11 project laterally from the opposite edges of the lower guide plate and overlap the front and rear edges of the sides 4 and 5 to hold the plate from longitudinal movement and provide 60 seats for the vertically adjusting screws of the upper guide plate 7. The upper guide plate 7 has arms 12, 12 and 13, 13 which overlap the sides 4 and 5 and hold the plate from longitudinal movement, and it is also 65 provided with cheeks 14, 14 near its forward end which contact with the sides 4 and 5, and hold the forward end of the upper guide plate from lateral movement, while the rear end is capable of sidewise adjustment by 70 means of horizontally adjusting screws.

The upper plate 7 is vertically adjusted by screws 15, which pass through holes in the arms 12, 12 and 13, 13 and have their lower ends seated on the arms 10, 10 and 11, 11 of 80 the lower guide plate, and carry nuts 16 which are screwed up or down and serve to support the upper guide plate. The rear end of the upper guide plate 7 is adjusted 85 sidewise by the screws 17, 17 which are screwed into the sides 4 and 5 and bear against the edges of the guide plate 7.

The sides 4 and 5 have a cross bar 18, in which is held a clamping screw 19, bearing against the upper surface of the upper guide 90 plate to hold it in contact with the nuts 16. The guide plates 6 and 7 may have the opposing surfaces plain to suit the sides of a flat bar, or they may be grooved, as in the present instance by grooves 20 and 21, adapted 95 to receive a lozenge shaped bar in cross section as shown at 22. The grooves 20 and 21, are adapted to receive a lozenge shaped bar 22, as it is delivered from the pair of rolls B, C with its longest diameter, as indicated by 100 the broken line a, a, lying in a horizontal plane and the upper and lower guide plates 6 and 7 are arranged to bear against opposite edges and upon opposite sides of the bar, while the center of the grooves are sufficiently cut away to afford clearance for the intermediate angles of the bar.

The surfaces of the guide plates contacting with a bar passing between them is slightly warped or twisted so as to impart an initial 110

twist to the bar in its passage through the guide plates. The present guide plates 6 and 7 are provided with longitudinal grooves 20 and 21, and the edges of the grooves which bear against the acute angled corners of the lozenge shaped bar lie in planes which are slightly twisted so as to impart an initial twist to the bar. In Fig. 6, the position of the bar 22 is shown as it enters between the 5 guide plates, with its longest diameter in a horizontal plane, as shown by the broken line a, a , but the plane of the edges of the grooves are slightly warped or twisted so that in its passage through the guide plates one 10 edge of the bar is tipped as shown in Fig. 7, and indicated by the inclination of the broken line b, b , to a horizontal plane. This tipping of the bearing surfaces of the plates gives an initial twist to the bar, as shown in 15 Figs. 6 and 7, and causes a varying degree of pressure to be imparted to the edges of the bar, corresponding to the force required to 20 twist the bar.

The amount of initial torsion or twist 25 thereby given to the bar, by its passage through the guide, is sufficient to rotate the bar a one quarter turn by the time the bar reaches the next succeeding pair of rolls, and the amount of initial twist can be varied by 30 the adjustment of the upper guide plate 7. The vertical adjustment of the upper guide plate is accomplished by raising or lowering the nuts 16 on the screws 15, and the horizontal adjustment is brought about by the 35 screws 17, 17, held in the sides 4 and 5.

The base plate 1, with its sides 4 and 5, form a supporting frame for the guide plates 6 and 7, the lower of which is removably held in the frame, but stationary by means of the 40 contact of its cheeks 8 and 9, and its arms 10 and 11, which engage the sides 4 and 5. The upper guide plate is also removable from the frame and is held at the proper distance from the lower plate by the screws 15 and nuts 16. 45 The upper guide plate is held in position by the clamping screw 19, held in a removable cross bar 18, whose opposite ends pass under the projecting lips 4^a and 5^a. By loosening the clamping screw 19, the cross bar 18 and 50 the guide plates 6 and 7 are all easily removed, allowing other guide plates to be inserted adapted to bars of different shapes and sizes.

What I claim as my invention and desire 55 to secure by Letters Patent is:—

1. A delivery guide for rolling mills, comprising a pair of guide plates adapted to receive a bar between them with the opposing surfaces of said guide plates warped or 60 twisted and arranged to bear with varying degrees of pressure against the opposite edges of the bar, thereby imparting a torsional movement to the bar as it passes between said plates, and means for adjustably 65 regulating the amount of clearance between

said plates, whereby the difference in the degree of pressure imparted to the different sides of the bar may be varied.

2. A delivery guide for a rolling mill, comprising a pair of guide plates adapted to receive a moving bar and bear against the opposite edges and opposite sides thereof and impart a torsional movement to said bar as it passes between said guide plates, adjusting screws carried by one of said plates and bearing against the other of said plates, nuts held on said screws by which the space between said plates is adjusted and means for clamping the plates, substantially as described.

3. A delivery guide for a rolling mill consisting of a pair of guide plates having warped opposing surfaces adapted to bear against the opposite sides of a bar passing between them and impart a torsional movement thereto, and means for laterally adjusting one end of one of said plates relatively to the other of said plates, whereby the position of the warped surface of one of said plates is varied relatively to the warped surface of the other of said plates.

4. In a delivery guide for rolling mills, the combination of a base plate having a pair of vertical sides, a pair of guide plates held between said sides and having opposing faces adapted to engage a bar and impart a torsional movement thereto as it passes between them, means for holding one of said plates in a stationary position on said base plate, means held by said base plate for laterally adjusting one end of the other of said guide plates, and means for adjustably varying the distance between said plates, substantially as described.

5. In a delivery guide for rolling mills, the base, a stationary guide plate supported thereon, and provided with seats of adjusting screws, an adjustable guide plate, screws held thereby and bearing on said seats, adjusting nuts on said screws and bearing against said adjustable plate, and a clamping screw bearing against said adjustable plate to hold it in contact with said adjusting nuts, substantially as described.

6. In a delivery guide for rolling mills, the combination with a lower stationary grooved guide plate, of an upper adjustable grooved guide plate supported upon said stationary guide plate, and means for the lateral adjustment of one end of said upper guide plate relatively to said lower guide plate, whereby its alignment with said stationary guide plate is controlled, said guide plates having opposing surfaces by which an initial torsional movement is imparted to a bar during its passage between them.

7. A delivery guide for rolling mills, comprising a supporting frame, a stationary guide plate and an adjustable guide plate held in said frame, said guide plates having opposing surfaces which are warped or

twisted to impart an initial twist to a bar during its passage between them, and means for varying the clearance between said plates in order to control the amount of twist imparted to the bar.

8. In a delivery guide for rolling mills, the combination with a base, of a pair of guide plates supported on said base, one of said plates being stationary, and means for the independent adjustment of the rear end of

the other of said guide plates relatively to said stationary plate, said guide plates having warped opposing surfaces, whereby a torsional movement is imparted to a bar passing between them.

15

Dated this 10th day of December 1902.
